UNITED STATES PATENT OFFICE.

WILLIAM T. ANDREWS, OF BOSTON, MASSACHUSETTS.

FEED-WATER HEATER.

SPECIFICATION forming part of Letters Patent No. 361,803, dated April 26, 1887.

Application filed January 28, 1887. Serial No. 225,790. (No model.)

To all whom it may concern:

Be it known that I, WILLIAM T. ANDREWS, a citizen of the United States, residing at Boston, in the county of Suffolk and State of Massachusetts, have invented certain new and useful Improvements in Feed-Water Heaters; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 This invention relates to improvements in "feed-water heaters," so called. These feeders are generally arranged with a continuous coil or coils of pipe through which feed-water is permitted to pass. While in its passage 20 therethrough it is subjected to the influence of steam, which surrounds and circulates about said coil.

25 My improvements pertain more particularly to the class of feed-water heaters above presented in which corrugated tubing is employed; but in the use of this tubing, which is very much thinner than plain tubing, some objections occur, which I have endeavored to overcome and which is the object of this invention.

30 The drawings accompanying this specification represent, in Figure 1, a central vertical sectional elevation of a feed-water heater embodying my improvements. Fig. 2 is a plan of the same, in which plain tubing is employed.

35 Fig. 3 is an enlarged section showing the manner of connecting the annular tubes to the central tube. Fig. 4 is a section, and Fig. 5 a plan of the same which represent a modification in the disposition of the annular tubes.

40 Hitherto certain objections have existed in the coil feed-water heaters as now constructed with corrugated tubing. This latter is decidedly superior to the plain tubing, since a thinner metal may be employed, greater efficiency in the transmission of heat is acquired, while superior strength and increased surface are gained by the corrugations. It has been found, however, that when the coil is employed for the transmission of the feed-water, and, 45 moreover, since said coil is secured only at its outlet and inlet ends to the steam-jacket, a certain vibration and spring are caused at such

points of juncture, owing to the extreme flexibility of the tubing which forms the coil. Furthermore, friction and wear are consequently 55 the result between the several turns composing the coil, and the life of the latter is very much impaired and shortened.

The primary object of my invention is to avoid this difficulty and yet continue the use 60 of the corrugated tubing, if desired, with all its inherent advantages. At the same time I wish to obtain greater heating-surface in the same space, and thus derive greater benefit from the steam-supply, preferably exhaust, as it circulates about the coil.

In the accompanying drawings, A represents a closed cylindrical vessel or jacket provided with supply and outlet passages *a* *b*, respectively, by which a flow of steam is maintained 70 therethrough. This jacket is mounted upon and bolted to a second closed vessel, B, which serves as a base for the heater as an entirety and is used as a settling-chamber and furnished with an outlet-pipe, *c*, through which sediment 75 from the water can be discharged and the heater cleansed. Centrally disposed upon the top of this chamber B, and in the present instance forming part of the same, rises a hollow vertical tube, C, which extends to the closed top 80 of the jacket A and is bolted thereto. Furthermore, a supply feed-water pipe, *d*, is entered into the chamber B, while the discharge-pipe *e* is arranged to engage with the central tube, C, at the top and delivers the hot water, 85 which naturally rises and collects there, to a boiler or other apparatus to be supplied.

To prevent vibration and wear of the continuous length of coiled pipe as now employed, I have subdivided it into a series of short annular tubes, *s* *s'* *s''* *s'''* *s''''*, &c., preferably circular in shape. These tubes are to be disposed about the tube C and secured thereto in the manner as indicated in Fig. 3 of the drawings. The tube C is cast with perforations, spirally or otherwise arranged, to admit the ends *f* *f'* of the tube over bosses *g* *g'*, which are formed about said perforations. The ends of the tubes are forcibly thrust over said bosses, and a binding-ring, *h*, shrunk or forced exteriorly about the 90 whole, locks them securely to the tube. These annular or semi-annular tubes may be secured to the tube C in several other well-known ways, and the arrangement of said tubes within the 95 100

shell of the tube C may be changed or altered at pleasure. I do not desire to be limited to the precise mode of arranging nor to the method of attaching said tubes to the main support-
5 ing-tube C. To prevent free passage of the water through the bore of the tube C before being thoroughly heated, I have inserted partitions *i*. Consequently the water under the action of the pump (not shown) is estopped from pass-
10 ing directly upward through the tube C and compelled to circulate through the tubes *s*, &c., in its passage through the heater.

In Figs. 4 and 5 I have shown a modified arrangement of the annular tubes *s* *s'* *s''* about the central one, C, wherein said tubes are disposed in four vertical series, the latter in quadrature about said tube C. By this method of isolating the tubes *s* each one is kept apart from the adjacent ones, but little vibration occurs, and
20 all attrition between the individual parts composing the heater is obviated.

When in operation, steam enters at the top of the jacket A through the inlet-aperture *a* and escapes at the bottom by way of the pipe
25 *b*, or viceversa. On the other hand, the feed-water enters at the bottom in the chamber B, thence is forced up the tube C until it reaches the first partition *i*, whence it is diverted and compelled to traverse several of the lateral
30 tubes, the lower ends of which are beneath the partition, while their upper extremities are above said partition. In its course there-

through the water becomes thoroughly heated. I find that when these annular tubes *s* are obliquely disposed with regard to the axis of
35 the central tubes, the natural flow of water upward as it becomes heated is accelerated. However, I do not wish to confine myself to this precise position, since they may be set at right angles to the axis of said tube, nor in the 40 direction and flow of the water or steam supply, since they may be reversed and changed to suit varying conditions or position of the heater.

I claim—

1. In combination with the water-chamber B and steam-jacket A, the hollow tube C, transversely divided by the partitions *i* and furnished with a series of independent annular tubes, *s*, all operating and arranged substantially as and for the purposes herein set forth.

2. The steam-jacket A, having inlet and outlet passages *a* *b*, respectively, the chamber B, with its feed-pipe *d*, in combination with the hollow tube C, interconnecting the supply-chamber B with the discharge feed-water pipe *e* and furnished with a series of independent annular tubes, *s*, substantially as described.

In testimony whereof I affix my signature in presence of two witnesses.

WM. T. ANDREWS.
